CLAIM

The ornamental design for a secure wall cable box, as shown and described.

DESCRIPTION

FIG. 1 is a front perspective view of a secure wall cable box with access doors in a closed position;
FIG. 2 is a front elevation view thereof;
FIG. 3 is a left, side elevation view thereof;
FIG. 4 is a right, side elevation view thereof;
FIG. 5 is a back elevation view thereof;
FIG. 6 is a top plan view thereof;
FIG. 7 is a bottom plan view thereof; and,
FIG. 8 is a front perspective view of a secure wall cable box with access doors in an opened position.
The broken lines shown represent unclaimed subject matter and form no part of the claimed design.
